UNITED STATES PATENT OFFICE.

HERMAN BESSER, OF ALPENA, MICHIGAN.

CONCRETE-MIXER.

No. 879,808.

Specification of Letters Patent.

Patented Feb. 18, 1908.

Application filed April 16, 1907. Serial No. 368,504.

To all whom it may concern:

Be it known that I, HERMAN BESSER, a citizen of the United States, and a resident of Alpena, in the county of Alpena and State of Michigan, have invented a new and Improved Concrete-Mixer, of which the following is a full, clear, and exact description.

My invention relates to machinery for working plastic substances, and more particularly to a type of machine suitable for mixing concrete and other moldable materials employed in building.

I have noticed that in mixing different kinds of cement products, for the purpose of making building blocks, brick, etc., considerable trouble is frequently experienced because the material must be used in a comparatively dry state. This is usually necessary because the material adheres to the plates of the machine. As a result it is difficult to make blocks which are waterproof. It is absolutely necessary to have an adequate supply of water in mixing concrete in order that good work may be done.

It should be borne in mind that by first thoroughly mixing the different materials in a dry state, then adding water in adequate quantity to insure perfect plasticity and to compact the material, it is very difficult to confer upon the blocks or other materials sufficient stability to enable them to be removed from the machine. Hence, in the present invention I seek to not only add an adequate supply of water to reduce the composite material to proper consistency, but further to add a quantity of dry material for the purpose of taking up the excess of water by hydration, and thus conferring upon the finished material a suitable consistency.

Reference is to be had to the accompanying drawings forming a part of this specification, in which similar characters of reference indicate corresponding parts on all the figures.

Figure 1 is a plan view of a machine made in accordance with my invention, showing the hopper provided with angular compartments for holding the various materials to be mixed, and also showing the various stationary baffles used for manipulating the materials as the latter are carried around; Fig. 2 is a vertical cross section on the line 2—2 of Fig. 1, looking in the direction of the arrow, and showing the relative arrangement of the hopper, the turntable, the stationary baffles,

and the gearing for actuating the turntable; Fig. 3 is a cross section through the hopper, showing the various gates and outlets for the materials; and Fig. 4 is a central vertical section on the line 4—4 of Fig. 3, looking in the direction of the arrow and showing the means for adjusting the gates by hand.

Mounted centrally within a framework 5 is a cup-bearing 6 provided with an anti-friction ball 7, upon which rests a vertical shaft 8. This shaft turns in a bearing 9 supported upon a trestle 10. Projecting inwardly from the framework 5 are lugs 11, supporting a stationary disk 12 bolted thereto. A hopper 13, of cylindrical form, is let into the disk 12 and supported stationarily in relation thereto. A ring 14 braces the hopper relatively to the disk 12 and holds these parts securely together. An annular band 15 encircles the framework 5 and strengthens the same. A revoluble table 16, of circular form, is provided with an annular step 17 concentric thereto. The plane of this step is of a lower level than that of the table 16. The step 17 and table 16 are connected together by a portion 18 integral therewith, as will be understood from Fig. 2. The object of the step in the disk is to keep part of the disk at all times dry, so that a perfectly dry mixture can be made before water is added. A pipe 17^a is used for showering water upon the step 17 and the materials carried thereby, the water being added to the materials on the lower and outer part of the disk at the point where it first drops over the step and upon the lower plane of the disk, the step preventing the water from coming in contact with the upper plane of the disk where the dry mixing is done.

The annular step 17 rests upon an annular gear 19, being secured directly to the same, and this gear meshes with a pinion 20 mounted upon a revoluble shaft 21. This shaft turns in a bearing 22 which is secured to the frame 5 and is fitted with a pulley 23 for the purpose of applying power thereto. The shaft 21 is provided with a hand-crank 24 whereby it may be turned. In other words, the device is fitted for rotation by either power or hand, as the case may be.

Mounted centrally upon the revoluble table 16 is a packing ring 26 of triangular cross section, as indicated in Fig. 2. The upper edge of this ring fits into an annular

groove 27 which is raised in the bottom of the hopper. The purpose of this arrangement is to prevent undue accumulation of material underneath the hopper, and especially the center of the same. The packing ring 26 serves as a barrier within which the material can not pass. This ring may be of any desired material, such as rubber or metal.

10 Mounted rigidly within the hopper 13 are partitions 28, 29, 30, whereby the interior of the hopper is divided into radially disposed compartments. The bottom of the hopper is shown at 31 and is provided with arcuate openings 32 which merge into larger openings 33, of the shape indicated in Fig. 1. Guiding walls 34, 35, 36, are provided, and the openings 33 are bounded upon the inner side by these walls.

15 20 Each partition 28, 29, 30, is provided with a gateway 28^a disposed adjacent to its bottom, which are in alignment with one of the arcuate openings 32 (see Fig. 3). Each gate 37 is operated by a hand-lever 38. The latter is mounted upon a pivot 39 serving as a journal, and is also connected by a pivot 40 with the upper end of the gate. A number of holes 41 are provided for receiving a pin 42, the latter passing through the hand-lever 38. In order to raise or lower the lever so as to adjust the vertical height of the gate 37, the hand-lever 38 is raised or lowered, the pin 42 being first removed, and then replaced. This will be understood from Fig. 35 4. By this arrangement the operator can adjust the outlet capacity of the several gates 37 at will and can render the capacity of one gate independent of that of another.

25 30 Mounted upon the stationary disk 12 and adjustable relatively thereto, are a number of baffle plates 44, 45, 46, arranged substantially in the form of a circle and placed at different angles relatively to each other in such manner as to guide, in a sinuous path, a substance resting upon the revoluble table 16.

35 40 At 47, 48 are baffles somewhat similar to those just mentioned, but having a slightly different shape, for the purpose of guiding the material in a slightly different path, for a purpose hereinafter described. It will be noted that the baffle plates 45 are a little further outward than the baffles 46. This facilitates the passage of the material in a sinuous path. A number of baffle plates 49, 45 50 are supported by the disk 12 and reach directly into engagement with the annular step 17. For this purpose the disk 12 is slotted, and the baffle plates extend vertically through it, being each adjustable with reference to the disk. All of the baffle plates used are mounted in the manner indicated in Fig. 2. That is to say, the baffle plates 49, 50, have their lower edges in a lower plane than is the case with the baffle plates 45, 46 (see Fig. 2). A guide plate 51, supported in

like manner as the baffle plates, is employed for directing the discharge of the material from the machine. The baffle-plates 45, 50 and the guide-plate 51 are provided with slots 52, through which extend bolts 53, the latter passing through supporting-brackets 54 mounted rigidly upon the disk 12 (see left-hand portion of Fig. 2). The various baffle-plates and the guide-plate 51 may be adjusted vertically. This is to compensate for wear at the bottoms of the various plates.

5 10 At 55 is a reservoir for holding a drying material. This reservoir is provided with an opening 56 for discharging the material upon the revoluble table 16.

15 20 My machine is used as follows: Suppose that I desire to make concrete. I place in the hopper the several separate quantities of sand, cement and gravel or crushed stone. The various gates are adjusted and power is applied to the machine. The revoluble table 16 and step 17 begin to turn. The dry materials flow out through the apertures 32, 28^a and 33. The rotation of the revoluble table, by carrying away the portion first making its appearance, makes room for another portion, so that the outflow of the materials is continuous. There are thus three streams of material, and upon reaching the wall 34 they merge into a single stream. The various baffles 45, 46 cause the material to turn over and over, so as to render the admixture thorough. This is while the materials are in a dry state. As soon as the mixture passes out upon the step 17 it is showered with water from the pipe 17^a. This water flows continuously while the machine is in action.

25 30 Care should be exercised to see that enough water is added to make a good quality of concrete. In this condition the material is too soft to be used for many purposes. As the material winds its way sinuously around, however, it comes to the reservoir 55 which, as above stated, is filled with a drying material, such, for instance, as powdered lime, or any other substance capable of taking up water by hydration. The wet concrete receives a proper proportion of this drying material and continues its way sinuously around, being baffled back and forth and finally lodging upon the step 17. Here it is again baffled inwardly and outwardly until it has had sufficient time and proper manipulation to enable the drying substance contained in it to reduce the entire mass to proper consistency to be molded. At last the finished material arrives at the guide-plate 51 and is ejected from the machine in the form of a continuous stream. If now the operator finds that for any reason the supply of a particular ingredient from the hopper is out of proportion he can, by adjusting one of the gates, correct this defect while the machine is in action. The gates are so posi- 100 105 110 115 120 125 130

tioned and adjusted as to feed out the different materials and bring them together at the points where they engage the baffles.

Having thus described my invention, I claim as new and desire to secure by Letters Patent:

1. The combination of a revolute table, a stationary hopper mounted thereover, a packing engaging said revolute table for preventing entry of materials from said hopper to certain portions of said revolute table, and stationary baffles disposed adjacent to said revolute table and in the path of travel of materials discharged from said hopper.

2. The combination of a table provided with a plurality of portions having different levels separated from each other, means for mixing upon one of said portions materials in a dry state, mechanism for transferring said materials thus mixed to the other portion, and mechanism disposed adjacent to said last-mentioned portion for wetting said materials.

25 3. The combination of a stationary mem-

ber provided with slots, baffles mounted within said slots, means for adjusting said baffles in a plane crossing the general direction of said stationary member, a revolute table provided with a plane surface and with a step, said plane surface engaging one of said baffles, and said step engaging another of said baffles, and means for turning said table relatively to said stationary member.

4. The combination of a hopper provided with a plurality of compartments, a plurality of separate gates for discharging material from the compartments, a revolute table disposed adjacent to said hopper and adapted to receive said materials when discharged therefrom, means for turning said table, and stationary baffles disposed adjacent to said table.

In testimony whereof I have signed my name to this specification in the presence of two subscribing witnesses.

HERMAN BESSER.
